COMBINED MOWER, CONDITIONER AND WINDROWER

Merle K. Burkhart, Ferol S. Fell, and Cecil L. Case,
Newton, Kans., assignors to Hesston Corporation,
Hesston, Kans.

Filed Sept. 9, 1971, Ser. No. 179,249

Term of patent 14 years

Int. Cl. D15—03

U.S. Cl. D40—1 E

Fig. 6.

FIG. 1 is a perspective view showing one side of a combined mower, conditioner and windrower made according to our present invention;

FIG. 2 is a perspective view showing the opposite side thereof;

FIG. 3 is a perspective view showing the back thereof;

FIG. 4 is a perspective view showing the front thereof;

FIG. 5 is a perspective view showing the top and front thereof; and

FIG. 6 is a top perspective view taken from the back of the windrower.

We claim:

The ornamental design for a combined mower, conditioner and windrower, as shown and described.
